Primary Examiner — George D. Kirschbaum*Assistant Examiner* — Lillian Windham(74) *Attorney, Agent, or Firm* — CANTOR COLBURN LLP(57) **CLAIM**

The ornamental design for a SOUNDER STROBE, as shown and described.

DESCRIPTION

FIG. 1 is a perspective view of a sounder strobe;
FIG. 2 is a front view of the sounder strobe;
FIG. 3 is a rear view of the sounder strobe;
FIG. 4 is a left side view of the sounder strobe;
FIG. 5 is a right side view of the sounder strobe;
FIG. 6 is a top view of the sounder strobe;
FIG. 7 is a bottom view of the sounder strobe.
The broken lines illustrate portions of the rear of the design that form no part of the claimed design.
